COMBINED CORSET AND DIAPHRAGM SUPPORT

Bertha M. Stradling, Blair, Nebr.

Application June 2, 1932, Serial No. 614,896

1 Claim. (Cl. 2-43)

This invention relates to a combined corset and diaphragm support, and has for its object, broadly, to provide a corset of such construction and arrangement of parts that it will tend to maintain the body in a symmetrical form and will be more comfortable to the wearer than ordinary.

One of the objects of the invention is to provide such a construction for the top of the corset that it will not unduly press the body and will not cause the flesh of the wearer to be pressed outwardly or rolled over the edge at the back or beneath the arms.

Another object is to provide such a construction that the front part of the corset at its top will not be unduly pressed against the body when bending forwardly.

The invention includes two, front, two-part lacings so that adjustments may be made conveniently to cause the garment to conform to the waist line, abdomen and thighs.

The invention includes a front row of clasps disposed at one side of the medial line so that clasping will be convenient, and that the corset at its front medial line may be smooth and free from buckling or undulations, and includes an elastic detachable stabilizing strip for the front which supports the diaphragm and takes up any slack at the back of the corset and which normally prevents any looseness or formation of folds of the front of the corset at its upper edges, and tends to depress the body at the diaphragm.

With the foregoing objects in view and others to be mentioned the invention presents a new and useful construction, combination and arrangement of parts as described herein and claimed, and as illustrated in the accompanying drawings, it being understood that changes may be made in form, size, proportions and minor details, said changes being within the scope of

40 the invention as claimed.

In the drawings, Fig. 1 is a view of the outer side of the corset when extended, the diaphragm supporting-strip being shown in dotted lines and broken away. Fig. 2 is a side view of the diaphragm supporting-strip. Fig. 3 is a perspective view showing the front of the corset when connected. Fig. 4 is a perspective view showing a side of the corset when connected.

Referring now to the drawings for a more particular description, numeral 10 indicates a rear corset-portion for embracing the back, the sides and hips of the wearer, said corset-portion at its upper extremity being provided with a fabric roll 11 and having attenuated vertical pockets 12 on its inner side extending from its top 11 to its

lower edge 13. Numerals 14 indicate comparatively short vertical pockets which are provided for the inner side of the corset-portion 10 and which extend downwardly from the roll 11 and receive suitable elastic stays. The parts of the 60 pockets 12 indicated at A receive suitable elastic stays and therefore the upper part is suitably reinforced. The lower parts of said pockets 12 and which terminate at the lower edge 13 of said corset-portion are not provided with stays, and therefore the lower part of said portion 10 which embraces the lower part of the back and hips will have a greater degree of flexibility than the upper part thereof and will not be reinforced.

Numerals 15 indicates an adjusting-strip connected at one of its edges with an edge of the corset-portion 10 by pairs of lacing-strands, the upper and lower pairs of said strands being indicated, respectively, at 16 and 17. Numeral 18 indicates a pocket which is provided for the inner 75 side of the adjusting-strip 15 for receiving an elastic stay, and at 19 are indicated fastening-elements which are provided for the adjusting-strip.

Numerals 20 indicates a second corset-portion 80 for embracing the front of the body, and this is flexibly connected at one of its edges with an edge of the corset-portion 10 by means of pairs of lacing-strands, the upper and lower pairs of said strands being indicated at 21 and 22 respectively. 85 Numerals 23 indicate pockets which are provided for the second corset-portion 20 for receiving elastic stays so that the said corset-portion 20 may be vertically reinforced. Numerals 24 indicate fastening elements for said corset-portion. 90

An angular opening is formed in the lower part of the front corset-portion 20 to open on its lower edge for an elastic gusset 25 to be secured therein.

Numerals 26 indicates a fabric strip which is 95 disposed transversely of the corset-portion 10 near its upper edge and secured to the inner side thereof for resisting stresses.

Numerals 27 indicate hose supporting-strips each secured to the lower extremity of the corset 100 in line with a reinforcing pocket 12 or 23.

It will be understood that when the corset is in use the elastic gusset 25 will be disposed at the medial line of the body at the lower part of the abdomen, the upper extremity of the corset-portion 20 being disposed approximately at the diaphragm. By referring to Fig. 1 of the drawings it will be seen that while the upper part of the corset-portion 10 is reinforced vertically with elastic stays the lower part thereof is devoid of 110

stays and therefore will not resist pressure, this being a desirable feature to permit this part of said corset-section, by operation of the elastic gusset 25, to conform to the curvature of the 5 thighs, the operation of said gusset being that, by its retraction it will cause the lower part of the corset-section 10 to be pressed and to snugly fit the curved portions of the thighs, and any buckling of this part of the garment will be prevented.

10 The diaphragm support consists of an elastic band 28 provided at its ends with fastening elements 29. The rear corset-portion near its top and adjacent to its side edge is provided with 15 fasteners 30, and the band 28, by use of these interengaging fastening elements, may be detachably secured to said rear corset-portion.

20 The elastic band 28, in form, is convergent toward its ends and is disposed on the outer side 25 of the corset-portions 10 and 20 at their upper extremities. It has an adequate width at its middle to overlie the upper part of the front corset-portion 20 and, when expanded, to extend above the top of said portion 20.

25 In operation, when the corset is in use, retraction of the elastic band 28 will prevent any looseness of the corset-portion 10 at the upper part thereof and will cause the vertical elastic stays in pockets A and 14 to become bent to conform 30 to the curvatures of the back of the wearer. Also the band 28 by its retraction, depresses the front part of the body at the diaphragm.

35 By referring to Fig. 1 of the drawings it will be seen that the pair of lacing strands 21 and 22, approximately midway between their ends, are connected with each other at intervals of their 40 lengths to provide a non-extensible part 31, and

therefore the adjacent edges of the adjusting strip 15 and corset-portion 10 at their upper or lower extremities may be disposed nearer to or further from each other as may be required for 80 adjustments, and similar adjustments may be made for the corset-portion 20 in connection with said corset-portion 10.

It is considered that the advantage derived by 85 use of the two front lacings and the adjusting-strip as shown and described is the fact that they cause adjustment of the form of this part of the body, the flesh at the abdomen being pressed laterally instead of being crowded toward the center.

90 I claim as my invention,—

95 In a combined corset and diaphragm support, a transversely and longitudinally reinforced corset-portion for the back, sides and hips of the wearer, a longitudinally reinforced second corset-portion connected at a longitudinal edge with a 100 longitudinal edge of the first named corset-portion for the front of the body, a longitudinally reinforced adjusting-strip disposed between said corset-portions and removably attached at an edge with an edge of the second corset-portion, 105 lacing-strands nonextensibly connecting an edge of the adjusting-strip with an edge of the first named corset-portion and arranged to permit adjustments of the upper or lower extremities of said adjusting-strip with the first named corset-portion to closed or spaced relation, and an elastic band detachably secured at its ends to the 110 upper part of the first named corset-portion and engaging said adjusting-strip and second corset-portion.
